CLAIM

The ornamental design for an ultrasonic cutting tool for medical use, as shown and described.

DESCRIPTION

FIG. 1 is a perspective view of an ultrasonic cutting tool for medical use showing our new design;

FIG. 2 is a top plan view thereof;

FIG. 3 is a side elevational view thereof, the view opposite that shown in FIG. 3 is identical to that shown in FIG. 3;

FIG. 4 is a bottom view thereof;

FIG. 5 is an end elevational view thereof; and,

FIG. 6 is an end elevational view thereof, opposite that shown in FIG. 5.

The broken line showing of the connector in FIGS. 1-4 is for illustrative purposes only and forms no part of the claimed design.
